ROLL-FORMING MACHINE

Robert M. Frame, Newark, N. J., assignor to The
Clark Thread Company, Newark, N. J., a cor-
poration of New Jersey

Application September 20, 1935, Serial No. 41,365

11 Claims. (Cl. 93—81)

This invention relates to a novel and improved form of roll-forming machine, the novel features of which will be best understood from the following description and the annexed drawings, 5 in which I have shown a selected embodiment of the invention and in which:

Fig. 1 is an elevation of the front of the machine;

Fig. 2 is an elevation of the rear of the machine appearing in Fig. 1;

Fig. 3 is a section approximately on the line 3—3 of Fig. 1;

Fig. 4 is a view approximately on the line 4—4 of Fig. 3, parts being omitted for the sake of 10 simplicity;

Figs. 5, 6, and 7 are views similar to Fig. 4 but showing the parts in different positions;

Fig. 8 is a section approximately on the line 8—8 of Fig. 6;

Fig. 9 is a section approximately on the line 9—9 of Fig. 6;

Fig. 9A is a view similar to Fig. 9, but on a smaller scale, and showing some of the parts in different positions;

Fig. 10 is a bottom plan view of the suction foot used with my invention;

Fig. 11 is a section approximately on the line 11—11 of Fig. 7;

Fig. 12 is a fragmentary section approximately 15 on the line 12—12 of Fig. 1;

Fig. 13 is a section approximately on the line 13—13 of Fig. 12;

Fig. 14 is a view of the apparatus shown in Fig. 12 as viewed from the opposite side thereof and with certain of the parts in different position;

Fig. 15 is a view approximately on the line 15—15 of Fig. 14;

Fig. 16 is a view, on the same plane as Fig. 14, 20 showing a detail of that figure;

Fig. 17 is a view of a section on an enlarged scale, approximately on the line 17—17 of Fig. 12;

Fig. 18 is a cross section in diagrammatic form 25 showing the finished roll.

The machine shown herein has been devised primarily for forming into rolls paper inserts for insertion in yarn balls, but is adapted for use wherever it is desired to form sheets of paper or the like into rolls for any other purpose. For the sake of convenience, I shall hereinafter refer to the sheets as being of paper, although the invention may be employed with other materials if desired.

30 The machine is shown as supported upon a

frame comprising a base 1 supported upon legs 2. Mounted on the base is a magazine 3 adapted to contain sheets of paper, and I provide intermittently operating means for feeding individual sheets one at a time from the magazine into position to be engaged by one of the roll-forming devices 4 upon a roller head 5. Before being fed from the magazine, each sheet has applied to it a small portion of glue so that, when formed into a roll, the glue will maintain the sheet in that 5 shape. A chain conveyor 6 is adapted to remove rolls from the devices on the roller head and deliver them to any desired point.

Referring now more particularly to Figs. 4, 5, 6, and 7, I will describe the means for removing 15 the sheets from the magazine and delivering them to the roll-forming devices. The sheets 7 are arranged in a stack on a table 8 having one end 9 thereof slightly raised as indicated, and the table is urged to the top of the magazine by any suitable yielding means, here exemplified as weights, one of which is shown at 10, connected to chains 11 running over pulleys 12, which chains are connected to the table through a frame 13. This arrangement urges the top of the sheets 7 20 against a shoe 14. By this arrangement the top sheet will always be maintained in substantially a predetermined position with the right-hand end, as viewed in Figs. 4, 5, 6, and 7, slightly raised 25 above the left-hand portion.

At the right-hand side thereof, the magazine is provided with a mouth 15 in the form of a funnel through which the sheets may be discharged to one of the roll-forming devices.

The sheets are fed from the magazine, according to the present embodiment, by a suction means intermittently operating to engage a sheet and carry it through the mouth 15. The suction means illustrated comprises a foot 16 which is vertically movable on an arm 17 mounted on a 30 pivot 18 slidably mounted in grooves 19 on the frame of the machine. This vertical movement is permitted by mounting the foot upon a pipe 20 slidable in a block 21 rockable on the pivot 18, and the pipe and consequently the foot is held 40 normally in raised position by means of a spring 22 acting between the block and a collar 23 secured to the pipe and which may be adjusted along the pipe to vary the force of the spring. The pipe is guided in its vertical movement by a 45 bracket 24 through a hole 25 in which the pipe passes and in which it may move to a limited extent transversely of its length.

Extending from opposite sides of the foot 16 are pins 26. These pins 26 run in cam grooves, 50

one of which is shown in each of Figs. 4, 5, 6, and 7. In order to prevent turning of the suction foot, a yoke 27 is provided sliding in a slot in a member 28 on the bottom of the arm 17 and held 5 in the slot by a pin 29.

The top of the magazine is open except under the shoe 14, and the movement of the suction foot is controlled by movement of the arm 17 and by movement of the pipe 20 on the arm. 10 These movements in turn are controlled by mechanism now to be described. The pins 18 and 26 are in pairs, as indicated in Fig. 3, and each pin of a pair is controlled by means identical with that for operating the other pin of the 15 same pair. Consequently, a description of the operation of one pin of each pair, as shown in Figs. 4, 5, 6, and 7, will suffice.

The arm 17 is operated by a crank 30 rotatably mounted at 31, and the movement of the pipe 20 20 on the arm is controlled by cams 32, 33, and 34, the cam 32 being pivoted at 35.

The suction foot 16 is in the form of a ring, as shown in Fig. 10, and inside of this ring is a chamber 36, at the top of which is a wall having 25 a plurality of orifices 37 through which suction is applied to the chamber. Then when the foot is placed in contact with a sheet of paper and suction applied through the orifices, the paper will be sucked up against the foot. According 30 to the selected embodiment, this suction is supplied by means of a pump 38 (Figs. 1 and 2) having an exhaust 39 and exhausting air from a vacuum tank 40 through a pipe 41. The vacuum tank 40 is connected to the suction foot 16 by 35 means of a pipe 42 having a valve 43 therein, and further by a flexible connection 44. Of course, it is to be understood that the orifices 37 communicate with the tank 40 through the pipe 20 and other connections described.

40 Suction is applied to a sheet of paper underneath the foot 16 at proper timed intervals by opening the valve 43, which may be done by means of a lever 45 (Fig. 5) pressing a valve stem 46 and connected by a link 47 with an arm 48 pivoted on the frame of the machine and having a cam roller 49 engaging the edge of the crank cam 30 which is shaped to form a cam, as plainly indicated. The crank cam 30 may be operated from the motor 50 through a worm drive 51 45 rotating a shaft 52 connected by a chain 53 to a shaft 54 which drives the shaft 31 by means of a chain 55.

50 Mounted on the frame adjacent the crank cam is a glue reservoir 56 having rotatably mounted therein a roller 57 rotated by means of a belt 58 from the shaft 31. Mounted on the arm 17 is a glue applicator, the details of which are shown in Fig. 11, and which comprises a rod 59 having a dauber 60. The rod 59 is slidably mounted on an ear 61 on the arm 17, and has connected to it a cam follower 62 engaging a cam 63 and yieldingly held against the cam by means of a plunger normally urged downwardly by means of a spring 64 in a cylinder 65.

55 The operation of the structure so far described will now be given, particular reference being given to Figs. 4, 5, 6, and 7.

Assuming first that the parts are in the position shown in Fig. 4, it will be seen that the 60 dauber 60 is in engagement with the glue roll 57 and that the cam 32 is in its uppermost position in which it is normally held by a spring 32'. The foot 16 is in engagement with the upper sheet 7, but no vacuum has been applied 65 to the foot. The crank cam 30 is rotated in the

direction indicated by the arrows, and when it has reached the position shown in Fig. 5, the pin 26 will have reached the left end of the cam 32. At this point, the spring 22 is compressed to its utmost, and as the pin 26 passes the end of the cam 5 32, the spring will cause it to rise abruptly to the approximate dotted line position shown in Fig. 5. Before this takes place, however, the valve 43 has been operated to place a suction on the foot 16, and as this foot rises to the dotted line position of Fig. 5, it will take the top sheet of paper with it. As the crank cam continues its rotation, it will increase and maintain the suction on the foot while the raised portion 39' of the 10 cam engages the roller 49.

15 Next, as shown in Fig. 6, the pin 26 will pass along the upper surface of the cam 32, forcing it downwardly against the action of the spring 32', and the sheet 7 will be dragged along the apron 15' forming the bottom of the mouth 15. As the 20 pin passes the right-hand end of the cam 32, the spring 32' will return this cam to the position indicated in Figs. 4 and 7, and by this time the roller 49 will have left the raised portion 39 of the crank cam. Similarly, the dauber 60 will be 25 descended to a position where it will engage the next sheet 7 in the pile in the magazine and will apply a dab of glue thereto. As plainly shown in Fig. 7, the sheet 7 which has been handled by the foot 16 will be released, since the suction has 30 been broken and the end of the sheet will have been projected through the mouth 15.

As a sheet is delivered from the mouth 15, it is received by one of the roll-forming devices 4, the details of which are best shown in Figs. 8, 9, 35 9A, 16, and 17. Each of these devices consists of a slotted sleeve 66 which is fixed in position on the head 5, this head being shown in the form of a disk rotatable with a shaft 67. Within each sleeve is mounted a spindle 68 rotatable on a 40 bearing 68' having a slot 69 extending diametrically therethrough. The head is intermittently rotated to bring one of the devices at a time to a position wherein, as a sheet is fed out of the mouth 15, it will pass through one of the slots 45 66 in the sleeve 66 into the slot 69 of the spindle 68 in that sleeve.

The spindle is rotated by any suitable means, here exemplified by a friction drive consisting of a driven element 70 in the form of a disk integral with the spindle 68 and adapted to engage a friction driving element 71. The element 71 is in the form of a roller mounted upon a lever 72 pivoted on the frame and having at its opposite end a cam roller 73 adapted to engage a cam 55 74 on a shaft 75, which may be driven from a shaft 54 by a chain drive 76.

By the above arrangement, the spindle will be rotated without rotation of the sleeve while the spindle is disposed at its station A at the mouth 60 of the magazine. The head is rotated intermittently in the direction indicated by the arrows in the various figures.

It is essential that when a spindle is presented 65 at the station A adjacent the mouth of the magazine, the slot 69 should be in line with that mouth so that a sheet of paper discharged from the mouth will enter the slot. For that purpose I provide two diametrically opposite pins 77 slidably mounted in the spindle 68 and spring-urged 70 towards the left of Figs. 8, 9, and 9A. One of these pins ordinarily will be received within a hole 78 in the head 5, and when in that hole the slot 69 will be in proper position. However, when the spindle is to be rotated to form 75

the roll, then the pin which is in the hole 78 should be released therefrom, and for that purpose I provide on the frame of the machine a cam 79 which is adapted to engage a pin 80 5 slidably mounted in the hole 78 and which will act to eject the pin 77 which happens to be in that hole.

This condition is shown in Figs. 8 and 9, where-as in Fig. 9A is shown the relation of the parts 10 when the spindle is held against movement by one of the pins 77 being received in the hole 78. Fig. 9A shows the parts shortly after the pin 80 has passed the cam 79. At that time the spindle 15 will still be rotating from the rotating action given it by the driving element 71, and normally this will be enough to cause one pin 77 to come in line with the hole 78. To insure that this should happen, however, I provide a shoe 81 adapted to engage the driven element 70 on each one of the 20 devices and cause it to rotate until one of the pins 77 actually does enter the hole 78. Each spindle is thus automatically and positively returned to a position where the slot 69 registers with the slots in its sleeve 66 whereby the sheet 25 of paper may be passed into the slot 69.

In order that the sheet of paper which is being inserted in the spindle slot shall not project beyond the sleeve for that spindle, I provide a stop 82 adapted to engage the end of the paper 30 and act as a stop. It is of course to be understood that the paper will pass through the slot in the spindle and be properly placed before the cam 74 permits engagement of the elements 70 and 71 to rotate the spindle.

The head 59 is intermittently rotated by means 35 of the belt 83 from the shaft 75, which will tend to rotate the head continuously, and the head is periodically held against rotation by means of a detent 84, best shown in Fig. 2, and which is 40 mounted on an arm 85 having a roller 86 adapted to engage a cam 87 likewise mounted on the shaft 75.

The detent 84 is adapted to engage a tooth 88, one of which is located on the head 5 adjacent 45 each spindle.

By the above arrangement it will be seen that an intermittent motion is given to the head, bringing one roll-forming device after another to the station A adjacent the mouth 15, and the cam 87 is so designed that, after a roll is formed 50 by a device at that station, the head is released so that it will bring another device to that station.

After a roll is formed at the station adjacent the mouth 15, the spindle on which the roll is 55 formed is held in fixed position by one of the pins 77, as was previously described, and upon rotation of the head 5 it will be brought to a station B, here shown as diametrically opposite the station 60 A. In other words, the individual roll-forming devices are indexed by rotation of the head.

At the station B I provide means for stripping the roll from the spindle upon which it has been formed, and this means is best shown in Figs. 3, 65 12, 13, 14, and 15.

Disposed coaxially with a spindle 66 when at the station B, is a tubular conduit 89 forming part of a conveyor and into which the rolls are forced by means to be described presently.

Each roll 90, as it is stripped from the spindle, has the cylindrical form indicated in Fig. 18. The daub 91 of glue indicated in Figs. 17 and 18 will hold the roll in this cylindrical form.

To strip a roll from a spindle, I provide an 75 ejector comprising two oppositely disposed pins

92 slidably mounted on a carriage 93 and spring-pressed towards each other by springs 94. The carriage 93 reciprocates in guides 95 supported on the frame with the machine, and having guide-ways 96 receiving ears 97 on the carriage. Reciproca-tion is caused by any suitable means, here shown as a crank disk 98 connected to the carriage by a link 99. The crank may be rotated by means of a belt 100 from the shaft 101 which in turn is driven by bevel gears from the shaft 10 54. The crank is held against rotation by means of a detent 102 adapted to engage lugs 103 on the crank and operated at predetermined intervals by means of a cam 104 (Figs. 1 and 3).

The pins 92, when the carriage is in the position shown in Fig. 14, will be disposed behind the particular roll 90 which is on the spindle at station B. Normally, the pins 92 will be pressed outwardly by the cam action of a sleeve 66 approaching the station B, and then will 10 enter the slots 66' in the sleeves 66 which are in alignment with the slot 69 in the spindle 68. Normally, the action of the springs 94 will be enough to force the pins 92 into the slots 66', but in order to insure proper registry of the 15 parts, I make each slot 66' of the form best shown in Figs. 14, 15, and 16, wherein it will be seen that the bottom of the slot, which is the right-hand thereof, as viewed in Fig. 14, is made of bayonet form with a right angle ex-20 tension 66'' which will permit the left-hand pin 92, as viewed in Fig. 15, to enter the slot without being cammed outwardly by the passage of the sleeve 66. For the sake of convenience in 25 manufacture, I make both slots 66' of identical 30 construction, since, when one pin 92 has reached its proper place in the end or bottom of the slot 66', as shown in Figs. 14 and 15, for example, then the sleeve 66 will be in position where the other pin 92 will automatically enter the other 35 slot 66'.

The carriage 93 is normally in the position shown in Fig. 14 so that as a sleeve containing a formed roll reaches station B, the pins 92 come 40 into position behind the roll in that particular 45 sleeve. Then the carriage will be operated by release of the crank 98 and move from the position shown in Fig. 14 to the approximate position shown in Fig. 12, carrying with it the roll on the spindle and thus stripping that roll 50 from the spindle. This movement carries the roll from the sleeve 66 into the conduit 89, this conduit having slots 105 in line with the slots 66', to receive the pins 92. Then the carriage will reciprocate back to the position shown in 55 Fig. 14 where it will be held by engagement of the detent 102 until time to strip a roll from another spindle.

In order to feed the rolls along the conduit 60 89, I provide conveying mechanism, exemplified by chain 6 having dogs 106 thereon at spaced 65 intervals and which are adapted to enter a slot 107 in the top of the conduit. These dogs are so spaced as to engage separate rolls and move them along the conduit. They may be discharged from the right-hand end of this conduit, as appears in Fig. 3, into any suitable receptacle, or, if desired, may be discharged on to another conveyor.

The chain 6 is actuated directly by move-70 ment of the carriage 93, as best shown in Figs. 12, 13, and 14. The chain is mounted on sprockets 108 and 109, and the sprocket 108 has there-on a plurality of pins 110, here shown as four 75 in number and equally spaced around the cen-

ter of the sprocket. The carriage has pivoted thereon a pawl 111 held against further counterclockwise movement, as viewed in Fig. 14, by means of a stop 112. Then as the carriage moves 5 towards the left in Fig. 14 or towards the right in Fig. 12, this pawl will engage one of the pins 110 and will cause rotation of the sprocket 108 and thus will actuate the chain 6. On its return movement, to the left in Fig. 12 and to the 10 right in Fig. 14, the pawl will engage the next one of the pins 110, but will ride past it without actuation of the sprocket, since the pawl is free to rotate in a clockwise direction, as viewed in Fig. 14. For example, if the pawl has 15 actuated the sprocket by engagement with the pin 110', as viewed in Figs. 12 and 14, then on its return it will ride freely over the pin 110'.

While I have shown the invention as embodied in a specific form, it is to be understood 20 that various changes in details may be made without departing from the scope of the invention, as defined by the appended claims.

I claim:

1. In a machine of the class described, a roll-forming device comprising a rotatable spindle having a slot therein, means for feeding a sheet of paper into said slot, means for then rotating said spindle, a head upon which said spindle is mounted, means to move said head to carry 30 said spindle to and from a station where said sheet may be fed thereto, a locking pin on said spindle adapted to enter a hole in said head to hold the spindle with the slot in position to receive said sheet, and means at said station to 35 eject said pin from said hole and maintain it out of said hole while the spindle is at said station.

2. In a machine of the class described, a roll-forming device comprising a rotatable spindle 40 having a slot therein, means for feeding a sheet of paper into said slot, means for then rotating said spindle, a head upon which said spindle is mounted, means to move said head to carry said spindle to and from a station where said sheet 45 may be fed thereto, a locking pin on said spindle adapted to enter a hole in said head to hold the spindle with the slot in position to receive said sheet, an ejector pin slidable on said head and in said hole, and a cam adapted to engage said 50 ejector pin to force and maintain said locking pin out of the hole when the spindle is at said station.

3. In a machine of the class described, a roll-forming device comprising a rotatable spindle 55 having a slot therein, means for feeding a sheet of paper into said slot, means for then rotating said spindle, a sleeve surrounding said spindle and having a slot registering with the spindle slot, said sleeve slot having an open end and having 60 a lateral extension at the bottom thereof, an ejector pin adapted to be received in said slots when in registry, and means to move said device to cause said pin to enter said slots at said lateral extension.

4. In a machine of the class described, a head 65 having a plurality of roll-forming devices thereon, each of said devices comprising a rotatable spindle having means adapted to engage a sheet, means to feed sheets of paper one at a time into 70 position to be engaged by one of said devices, means to intermittently move said head to bring each of said devices to a receiving station to receive one of said sheets and then to a discharging station, means to rotate the spindle of said device 75 vice when at said receiving station to form a roll

thereon, a reciprocating carriage at said discharging station having means to engage said roll and strip it lengthwise from the spindle, means to actuate said carriage, a conveyor to receive said roll as it is stripped from the spindle, 5 and means to operate the conveyor by movement of the carriage.

5. In a machine of the class described, a roll-forming device comprising a rotatable spindle having a slot therein, means for feeding a sheet 10 of paper into said slot, means for then rotating said spindle, a sleeve surrounding said spindle and having a slot adapted to register with the spindle slot, means to move said spindle to a station where said sheet may be fed thereto and 15 then to a discharging station, a reciprocating carriage at said discharging station having a pin adapted to enter said slots at the back of the roll on the spindle, means to hold said spindle with said slots in registry while at said discharging 20 station, and means to reciprocate said carriage to strip the roll from the spindle, said slots having open ends to permit said stripping.

6. In a machine of the class described, a roll-forming device comprising a rotatable spindle 25 having a slot therein, means for feeding a sheet of paper into said slot, means for then rotating said spindle, a sleeve surrounding said spindle and having a slot adapted to register with the spindle slot, means to move said spindle to a 30 station where said sheet may be fed thereto and then to a discharging station, a reciprocating carriage at said discharging station having a pin adapted to enter said sleeve slot at the back of the roll on the spindle, and means to reciprocate 35 said carriage to strip the roll from the spindle, said slots having open ends to permit said stripping, and said sleeve slot having a lateral extension at the bottom thereof to receive said pin as the sleeve approaches the discharging station. 40

7. In a machine of the class described, a roll-forming device comprising a rotatable spindle having a slot therein, means for feeding a sheet of paper into said slot, means for then rotating said spindle, a sleeve surrounding said spindle 45 and having an open-ended slot adapted to register with the spindle slot, means to move said spindle to a station where said sheet may be fed thereto and then to a discharging station, a conduit in line with said sleeve at said discharging 50 station and having an open-ended slot in line with the open-ended slot of the sleeve, a pin adapted to enter said sleeve at the back of the roll on the spindle, and means to move said pin in said aligned slots to strip the roll from the spindle 55 and force it into the conduit.

8. In a machine of the class described, a roll-forming device comprising a rotatable spindle having a slot therein, means for feeding a sheet 60 of paper into said slot, means for then rotating said spindle, a sleeve surrounding said spindle and having a slot adapted to register with the spindle slot, means to move said spindle to a station where said sheet may be fed thereto and then to a discharging station, a reciprocating carriage at said discharging station having a pin 65 adapted to enter said sleeve slot at the back of the roll on the spindle, means to reciprocate said carriage to strip the roll from the spindle, said 70 slots having open ends to permit said stripping, a conveyor having a conduit in line with said sleeve at said discharging station, to receive the roll stripped from said spindle, means to move rolls along said conduit independently of each 75

other, and means to operate said roll-moving means by movement of said carriage.

9. In a machine of the class described, a head having a plurality of roll-forming devices thereon, each of said devices comprising a rotatable spindle having a slot therein and a sleeve surrounding said spindle and having a slot adapted to register with the spindle slot, means to feed sheets of paper one at a time into position to be engaged by one of said devices, means to intermittently move said head to bring one of said devices at a time to a station where it will receive one of said sheets from said feeding means, means normally holding said spindle against rotation in said sleeve and with said slots in registry, means to release said holding means at said station, means operating at said station to rotate said spindle within said sleeve, whereby a sheet of paper inserted through said registered slots will be rolled around the spindle inside the sleeve, a discharging station to which said spindle with the paper wound thereon is brought by said intermittent movement, a reciprocating carriage at said discharging station having a pin adapted to enter said slots at the back of the roll on the spindle, said holding means holding said spindle in position wherein said slots again will be in registry after the spindle leaves said first-named station, and means to reciprocate said carriage to strip the roll from the spindle.

10. In a machine of the class described, a roll-forming device comprising a rotatable spindle having a slot therein, a sleeve surrounding said

spindle and having a slot adapted to register with the spindle slot, means for feeding a sheet of paper into said spindle slot through said sleeve slot, means for moving said spindle to and from a station where said sheet may be fed thereto, 5 means for rotating said spindle at said station, means for holding said spindle against rotation within the sleeve except at said station and with said slots in registry, and means to release said holding means while the spindle is at said station. 10

11. In a machine of the class described, a head having a plurality of roll-forming devices thereon, each of said devices comprising a rotatable spindle having means adapted to engage a sheet, means to feed sheets of paper one at a time into 15 position to be engaged by one of said devices, means to intermittently move said head to bring each of said devices to a receiving station to receive one of said sheets and then to a discharging station, means to rotate the spindle of said 20 device when at said receiving station to form a roll thereon, a reciprocating carriage at said discharging station having means to engage said roll and strip it lengthwise from the spindle, means to actuate said carriage, a conveyor to receive 25 said roll as it is stripped from the spindle, and spaced members on said conveyor so placed thereon as to be engaged by said carriage upon its stripping movement, whereby said stripping movement of the carriage will operate the conveyor intermittently. 30

ROBERT M. FRAME.
